UNITED STATES PATENT OFFICE.

ANTON BECKER, OF COLUMBUS, OHIO.

UNDERFRAME CONSTRUCTION FOR CARS.

No. 834,654.

Specification of Letters Patent.

Patented Oct. 30, 1906.

Application filed February 12, 1906, Serial No. 300,756.

To all whom it may concern:

Be it known that I, ANTON BECKER, a resident of Columbus, in the county of Franklin and State of Ohio, have invented certain new and useful Improvements in Underframe Construction for Cars; and I do hereby declare the following to be a full, clear, and exact description of the invention, such as will enable others skilled in the art to which it appertains to make and use the same.

My invention relates to metallic-car underframe constructions, and is in some respects an improvement upon my three prior patents, Nos. 763,841, 763,947, and 794,274.

15 The object of my invention is to provide an underframe construction for a car of the type illustrated in my above-mentioned patents in which a central girder with longitudinal cross-bearers is employed in combination with normally level floor-doors hinged at or near the top of the central girder adapted to swing down at the sides of the car to discharge the load, which can be easily and cheaply made from a relatively small quantity of material, which is very rigid and firm when constructed, is efficient in operation, and is not readily liable to get out of order. It consists in the novel method of supporting the side sills of the car, in the novel form of 20 hanger for the operating-shaft, in the novel form of bracing for securing the cross-bearers to the central girder, and in other details of construction which will be hereinafter more fully described and claimed.

35 In the drawings, Figure 1 is a central sectional detail view of a car of the type illustrated in my above-mentioned prior patents, and particularly the one having the door-operating mechanism of Patent No. 763,841, 40 embodying the improvements of my invention in their preferred form. Fig. 2 is a somewhat enlarged detail view of the hanger mechanism appearing at the left of Fig. 1. Figs. 3, 4, and 5 are detail parts of the device of Fig. 2 shown separately. Fig. 6 is a detail perspective view of brace-plates connecting the central girder and cross-bearers. Fig. 7 is a detail perspective view of a novel form of top plate for the cross-bearers, showing means for securing it to the stake and for supporting the side sills of the cars upon them. Fig. 8 is a central sectional detail view of a modified form of car in which the central girder is made deeper than in Fig. 1; 50 the same extending up into the underframe,

the cross-bearers therefore not extending entirely across the car.

Again referring to the drawings, the numeral 11 indicates the side plates, and 12 the top plates, of a central girder of the box type 60 extending longitudinally of a car, the same being joined together by angle-irons at the corners, as shown.

Extending across the bottoms of the side plates of the central girder at intervals and 65 secured thereto are the intermediate portions 13 of braces 32. Across the top of this central girder, extending from side to side of the car, as in my prior patents, are cross-bearers 15, preferably commercial rolled channel- 70 irons, having vertical webs and horizontal flanges 16 and 17 extending from one side thereof in the usual manner. These cross-bearers are placed upon the central girder at approximately equal distances apart longitudinally of the car, so that floor-doors 21 75 may be pivotally mounted between them in such a way that, as fully described in my prior patents, they will when swung up level with the tops of the channel-iron cross-bearers 80 form part of the level floor of the car and that when swung down to the dotted-line position of Fig. 1 they will be adapted to discharge the load at the sides of the car. These doors 21 are hinged upon a longitudinally-hinged rod 18, mounted in a plurality of castings 19, which are in turn mounted upon the I-beam 20, placed above the central girder and connected to the successive cross-bearers, as is fully described and claimed in 85 my prior application, Serial No. 268,805, filed by me May 29, 1905. The cross-bearers 15 are secured to and braced from the central girder by means of the novel form of brace-plates 25 and 26 illustrated in detail in 90 Fig. 6. These plates have, as shown, vertical flanges 27, adapted to be secured to the side plates 11 of the central girder by bolts or rivets 28, bottom flanges 29, adapted to be secured to the bottom angles of the central 95 girder and horizontal portions 13 of bottom braces 32 by means of the bolts or rivets 30, diagonal flanges 31, adapted to be secured to the upwardly-extending portions of the bottom braces 32 by means of bolts or rivets 33, and top lips 34, adapted to be secured to the webs of the channel-irons 15 by the bolts or rivets 36. These plates are, as shown, very broad in their width perpendicular to the flanges 31, so that they have great bracing 100.

strength and in addition to supporting the cross-bearers in the ordinary way give the car great lateral rigidity. The plates 25 and 26 upon opposite sides of the central girder 5 are connected together by means of cross-plates 38, placed inside the central girder, the same having flanges 39, which are engaged by the rivets 28, heretofore described.

Over the top of each cross-bearer I place a 10 suitable cover-plate or angle-iron 40, with downwardly-turned flanges 41, as is more fully described and claimed in my prior application, Serial No. 262,805. The cover-plate 40 is shown in detail in Fig. 7, and, as 15 shown in Fig. 1, said plates have end portions 43 extending beyond the ends of the cross-bearers, and suitable side stakes 44 are secured by bolts or rivets 46 to the ends of the cross-bearers, said bolts or rivets passing 20 through the webs of the cross-bearers and the shanks of the side stakes, which are turned toward the longitudinal central line of the car. The channel-irons or cover-plates 40 are cut away to form recesses or notches 48, 25 in which the shanks of the side stakes fit, and have upturned lips 49, adapted to bear against the flanges 50 of the stakes and be secured thereto by means of the bolts or rivets 51. Outside of the stakes and resting 30 upon the ends 43 of the cover-plates 40 I place side sills 53, preferably made of channel-irons, as shown, extending along the sides of the car, and secure the same to the stakes by means of the bolts or rivets 54 and bolts 35 or rivets 51. By this construction the stakes are given a very rigid attachment to the ends of the cross-bearers, and the side sills are supported by portions of the cross-bearers, (the cover-plates 40,) as well as by their bolt 40 or rivet attachment to the stakes, all of which gives a very strong yet economical construction.

The operating mechanism for the floor-doors 21 is that of my said prior patent, No. 763,841, in which a longitudinal shaft 60, 45 with a plurality of crank-arms 61 and intermediate common crank-pins 62, carrying rolls 63, bearing upon the under side of the successive floor-doors, is used, the same bearing 50 supported in suitable hangers upon the under side of the underframe, the form of which here shown is a part of my invention. These hangers consist of single pieces of metal bent in the form of a Y, with the bearing 55 for the shaft upon the lower end of each hanger. In detail they consist of said hangers having flanges 66 and 67, secured to the lower flanges of the cross-bearers by bolts or rivets 68, having also the inclined angular portions 69 and 70 of the Y and the normally opened upturned bearing portion 71 at the lower end of the Y, in which the shaft 60, heretofore referred to, rests and is journaled. These hangers are made more rigid upon the 60 under side of the cross-bearers by means of

the flat plates 73, secured to the webs of the cross-bearers by bolts or rivets 74, as shown, the plates themselves depending below the cross-bearers and having angular wings or lips 75 and 76 fitting in and engaging the angular portions 69 and 70 of the Y's and secured thereto on the side by bolts or rivets 78 and on the other side by removable bolts 79, adapted to secure in position removable angular pieces 80, having one arm adapted to fit under said bolt and the other arm adapted to bear against the shaft 60 and secure the shaft in the bearing, as shown. By this construction I obtain a very cheap hanger which is very rigid upon the under side of the cross-bearers, thereby rendering the shaft more accurately operable.

In Fig. 8 I have shown a modified form of structure using the bracing of my invention in which the central girder extends up into 85 the underframe of the car and the top plates 82 upon the cross-bearers extend through slots in the vertical web-plates of the central girder.

It is evident that many slight changes 90 might be made in the relative arrangement of parts shown and described without departing from the spirit and scope of my invention. Hence I would have it understood that I do not wish to confine myself to the 95 exact construction herein shown and described; but,

Having fully described my invention, what I claim as new, and desire to secure by Letters Patent, is—

1. In a car in combination with a car-underframe, a depending bracket secured thereto, a normally open upturned bearing on the bracket, a shaft resting in said bracket, and an angular cover for the bearing having one arm secured to the bracket and the other arm extending over the bearing.

2. In a car in combination with a car-underframe, a hanger depending from a member thereof, a shaft adjacent to the hanger and at right angles to the member to which it is secured, an upturned open bearing on the hanger supporting the shaft, and an angular cover having one arm secured to the hanger and the other arm holding the shaft in the bearing.

3. In a car in combination with a car-underframe, a hanger depending from a member thereof, a shaft adjacent to the hanger and at right angles to the member to which it is secured, and upturned open bearing on the hanger supporting the shaft, and an angular cover having one arm detachably secured to the hanger and the other arm holding the shaft in the bearing.

4. In a car in combination with a member of a car-underframe having a vertical web and a flanged bottom, a Y-shaped hanger secured at the tops of the Y to the flange of the underframe member, and a brace member

secured to the underframe member and to an angular portion of the Y of the hanger.

5. In a car in combination with a member of a car-underframe having a vertical web and a flanged bottom, a Y-shaped hanger secured at the tops of the Y to the flange of the underframe member, a reinforcing-plate secured to the web of the underframe member, an angular portion on said plate bent at right angles into contact with an adjacent angular member of the Y, and means for securing said angular member to the Y.

6. In a car in combination with a member of a car-underframe having a vertical web and a flanged bottom, a Y-shaped hanger secured at the tops of the Y to the flange of the underframe member, a reinforcing member secured to and depending from this underframe member, the depending portion being wedge-shaped to fit the angular portion of the Y of the hanger, flanges on the angular edges of said depending portion in contact with the angular portions of the Y, and means for securing said flanges to the hanger.

25 7. In a car in combination with a member of a car-underframe having a vertical web and a flanged bottom, a Y-shaped hanger secured to the web of the underframe member and depending therefrom, the depending portion being wedge-shaped to fit the angular portion of the Y of the hanger, flanges on the angular edges of said depending plate in contact with the angular portions of the Y and means for securing said flanges to the hanger.

35 8. In mechanism of the class described, in combination with a car-underframe having cross-bearers; side stakes secured upon the ends of the cross-bearers; plates over the cross-bearers notched to receive the shanks 40 of the stakes toward the center of the car, the plates over the cross-bearers, having portions extending beyond the stakes and side sills outside the stakes, supported on the ends of the plates and secured to the stakes.

45 9. In mechanism of the class described, the combination with a car-underframe having cross-bearers, T-shaped side stakes secured upon the ends of the cross-bearers with the shanks of the stakes toward the center of the car, plates over the cross-bearers notched to receive the stakes there being upturned flanges or lips near the ends of said plates upon the cross-bearers bearing against the flanges of the stakes, and means for securing 55 the said upturned flanges to the flanges of the stakes.

10. In mechanism of the class described, the combination with a car-underframe having cross-bearers, side stakes secured upon 60 the ends of the cross-bearers with the shanks of said stakes toward the center of the car, plates over the cross-bearers notched to receive the stakes, there being upturned flanges or lips near the ends of said plates upon the 65 cross-bearers bearing against the flanges of

the stakes means for securing the said upturned flanges to the flanges of the stakes, and horizontal side sills outside the stakes supported on the ends of said plates over the cross-bearers and secured to said stakes.

11. In a car, the combination of a longitudinal central girder and a plurality of cross-bearers upon the top thereof extending crosswise of the car, brace-plates upon opposite sides of the central girder lying in the transverse plane of the car having their upper edges secured to the cross-bearers, vertical flanges upon said plates secured to the vertical webs of the central girder, other flanges upon said plates secured to the lower angular flanges of the central girder, diagonal flanges upon said brace-plates and braces passing under the girder and secured to said diagonal flanges and the girder.

12. In a car, the combination of a longitudinal central girder and a plurality of cross-bearers upon the top thereof extending crosswise of the car, brace-plates upon opposite sides of the central girder lying in the transverse plane of the car having their upper edges secured to the cross-bearers, vertical flanges upon said plates secured to the vertical webs of the central girder, and other flanges upon said plates connected with the bottom of the central girder.

13. In a car, the combination of a longitudinal central girder and a plurality of cross-bearers, upon the top thereof extending crosswise of the car, brace-plates upon opposite sides of the central girder lying in the transverse plane of the car having their upper edges secured to the cross-bearers, and vertical flanges upon said brace-plates secured to the vertical webs of the central girder.

14. In a car, the combination of a longitudinal hollow central box-girder and a plurality of cross-bearers upon the top thereof extending crosswise of the car, brace-plates upon opposite sides of the central girder lying in the transverse plane of the car having their upper edges secured to the cross-bearers, vertical flanges upon said plates secured to the vertical webs of the central girder, other flanges upon said plates connected with the bottom of the central girder, diagonal flanges upon said brace-plates braces passing under the bottom of the central girder and secured to the diagonal flanges of the brace-plates, and a cross-plate inside the central girder secured to the webs thereof and to the diagonal braces.

15. In a car, the combination of a longitudinal hollow central box-girder and a plurality of cross-bearers upon the top thereof extending crosswise of the car, brace-plates upon opposite sides of the central girder lying in the transverse plane of the car having their upper edges secured to the cross-bearers, vertical flanges upon said brace-plates se-

5 cured to the vertical webs of the central girder, other flanges upon said plates connected with the bottom of the central girder, and a cross-plate inside the central girder secured to the webs thereof and to the diagonal brace-plates.

16. In a car, the combination of a longitudinal hollow central box-girder and a plurality of cross-bearers upon the top thereof extending crosswise of the car, brace-plates upon opposite sides of the central girder lying in the transverse plane of the car having their upper edges secured to the cross-bearers, vertical flanges upon said brace-plates secured to the vertical webs of the central girder, and a cross-plate inside the central girder secured to the webs thereof and to the diagonal brace-plates.

17. In an article of manufacture, a top 20 plate for a cross-bearer for a metallic car, consisting of a plate having notches in each end adapted to receive a portion of a car-stake, and upturned flanges adjacent to the notches bent out of the cross-plate, adapted to be secured to the flanges of the car-stake.

18. As an article of manufacture, a top 25 plate for a car cross-bearer, consisting of a flat plate having recesses near the ends adapted to have car-stakes fit therein, and portions extending beyond the openings for the car-stakes on which the side sills of the car may be supported.

19. In a metallic car, the combination of a central sill, cross-bearers thereon, and cover-

35 plates on said cross-bearers, of side sills mounted upon the cover-plates, hinged floor-doors in a plane below that of the side sills and means located below the hinged doors for opening and closing them.

20. In a car, the combination of a central 40 girder and cross-bearers thereon, and brace-plates connecting the sides of the central girder to the cross-bearers.

21. In a car, the combination of a central 45 girder, cross-bearers thereon, and diagonal brace-plates, each secured to the web of the central girder and to a cross-bearer.

22. In a car, the combination of a central 50 box-girder having an open bottom, cross-bearers, and brace-plates secured to the webs of said central girder and to the cross-bearers.

23. In a car, the combination of a central 55 box-girder having an open bottom, cross-bearers, brace-plates secured to the webs of the central girder and to the cross-bearers, and braces extending transversely across the open bottom of the central girder and secured at their ends to the outer edges of the 60 brace-plates.

In testimony whereof I have signed this specification in the presence of two subscribing witnesses

ANTON BECKER.
